M. MATHIEU, OF RICHMOND, VIRGINIA

HIGH TENSION IGNITION SYSTEM

Application filed July 12, 1930, Serial No. 467,561. Renewed June 4, 1932.

This invention relates to high tension ignition systems for internal combustion engines, and has in view to provide a simple inexpensive system of this character which 5 is highly efficient in operation.

According to the present practice, high tension ignition systems are inclusive as a rule of a switch or so-called breaker arm in the primary circuit of the system which is 10 maintained normally closed to permit a strong flux to build up in the winding of said circuit to develop a high voltage in the secondary circuit each time that the primary circuit is opened. Usually a relatively 15 strong spring is employed to urge the breaker arm to a circuit closing position, and an engine operated cam utilized to move said arm against the force of said spring to open the circuit at properly timed intervals.

20 At low engine speeds, systems of the foregoing character are amply efficient in operation, but above certain engine speeds such systems begin to lose their efficiency, until finally the system fails utterly to function 25 when certain high engine speeds are attained.

At low engine speeds the primary circuit remains periodically closed a sufficient length of time to permit a strong flux to build up about the coil in said circuit, and as a consequence 30 a high voltage affording a strong spark is induced in the secondary circuit when the primary circuit is opened. As the speed of the engine is increased, however, the time that the primary circuit remains closed between successive circuit opening movements 35 of the breaker arm is proportionately diminished, with the obvious result that the voltage in the secondary circuit is progressively lowered and the spark is correspondingly weakened. Thus, for each different engine speed within the operative 40 limits of high tension ignition systems employing a so-called breaker arm, there is a difference in the intensity of the spark, which is a serious disadvantage from many different viewpoints, the spark becoming weaker and weaker as the speed of the engine is increased and finally failing utterly, as heretofore stated, when a certain high speed of the 45 engine is attained, due to opening move-

ments of the breaker arm occurring so rapidly as not to permit the spring to function to move the arm to a closed position.

In ignition systems of the character mentioned where the intensity of the spark varies 55 with changes in the speed of the engine, a delicate adjustment of the contact points, one of which is carried by the breaker arm, is required to be maintained, and due to the destructive hammering action on these contact points during operation of the system, such contact points not only deteriorate rapidly, but their deterioration necessitates their frequent readjustment and replacement. Moreover, the breaker arm mechanism 60 constitutes one of the chief items of expense 65 in the installation and maintenance cost of ignition systems employing such mechanisms.

Accordingly, the present invention has in 70 view to provide a high tension ignition system which is effective to produce a spark of uniform intensity at all engine speeds, and to accomplish this purpose by the substantial 75 elimination of all mechanically operating elements such as the breaker arm and the related elements of most present high tension ignition systems, thereby to provide a system which is equally efficient in operation at all engine speeds, which is materially less expensive 80 to install and to maintain than most present systems, which eliminates the necessity for frequent and delicate adjustments of any part thereof, and which is thoroughly reliable in operation during long periods of 85 use.

With the foregoing and other purposes in view, the invention consists in the novel features of construction, combination and arrangement of parts as will be hereinafter 90 more fully described, illustrated in the accompanying drawing and defined in the appended claims.

In the drawing, wherein like characters of reference denote corresponding parts in the 95 different views:

Figure 1 is a diagrammatic illustration of a high tension ignition system embodying the novel features of the invention.

Figures 2 is a vertical section through the 100

distributor mechanism of the present system; and

Figure 3 is a sectional view similar to Figure 2 taken at right thereto.

5 By reference to the drawing it will be observed that the present ignition system comprises relatively few parts and that these are of such a simple nature as to possess long life and to be produced and embodied in the 10 system at relatively small cost.

In carrying the present invention into practice, according to a practical embodiment thereof, a source of current, such as an ordinary storage battery 10, is grounded at 15 one side, as at 11, and at its other side is connected by a conductor 12 with one end of a winding 13, the other end of which is connected with an arm 14 suitably urged normally into engagement with a contact 15 20 which is grounded as at 16. A core 17 of magnetizable material is disposed within the winding 13 and cooperates therewith to provide an electro-magnet with respect to which the arm 14 is suitably arranged so that when 25 current flows through said coil the arm is attracted by said magnet and is pulled from engagement with the contact 16, thereby opening the circuit which again is closed when 30 said arm, which is released by opening the circuit, moves to its normal position against said contact. A manually operable switch 18 is interposed in the conductor 12, and thus, when said switch is closed, the circuit through the winding 13 is alternately opened and 35 closed by the arm 14 as is manifest. Preferably, a condenser 19 is interposed between the arm 14 and the contact 15 for the usual purpose.

The foregoing elements constitute the primary 40 circuit of the present system, the secondary circuit of which is composed of a winding 20 disposed in suitable cooperative relation to the winding 13, and which is grounded at one end, as at 21, and connected 45 at its other end by a conductor 22 with a distributor mechanism designated generally as 23.

The distributor mechanism 23 includes a suitable base 24 through which extends a rotatable shaft 25 which is suitably driven at a proper rate of speed by the engine.

Mounted on the base 24 is a distributor cap 26 of suitable insulating material, such as hard rubber, having a central contact 27 55 and one or more distributing contacts 28, the number of which is dependent, of course, upon the number of engine cylinders.

Mounted on the shaft 25 for rotation therewith is a distributor arm 29 which also is 60 formed of suitable insulating material such as hard rubber and which has embedded therein a conductor 30, the same being exposed at one end for continuous engagement with the central contact 27 and exposed at its other end for cooperation with the distributor

ing contact or contacts 28, as the case may be.

The contacts 28 and the exposed ends of the conductor 30 preferably are of very small area and do not extend appreciably beyond the surfaces of the cap 26 and the distributor arm 28, respectively, through which they are exposed, thereby to guard against undesirable jumping of the high tension current between said contacts.

The conductor 22 of the high tension circuit of the system is connected with the contact 27, and from the contact or contacts 28, as the case may be, a conductor or conductors 31 is or are connected with the usual spark plug or plugs 32 of the engine cylinder or 80 cylinders.

In view of the foregoing, the operation of the system will be apparent as follows: Upon closing the switch 18 the primary circuit is energized and said circuit is rapidly opened and closed by the arm 14 continuously and at a fixed rate of speed for all engine speeds so long as said switch remains closed, thereby inducing a substantially continuous and uniform high voltage current in the secondary 90 circuit, and as the distributor arm 29 rotates with the shaft 25, establishing a circuit between the conductor 22 and the contact or contacts 28, this high tension current is distributed to the plug or plugs 32, the intensity 95 of the spark obviously being uniform for all engine speeds.

If desired, means may be provided between each adjacent pair of the contacts 28 to ground the high tension current in any instance where the system includes two or more such contacts 28, thereby to provide a positive means of preventing the high tension current from jumping between any two of said contacts 28 or from the conductor 30 to other 100 than a desired contact 28. Conveniently, such means may comprise a conductor 33 embedded in the cap 26 between each adjacent pair of the contacts 28, and having one end exposed within the cap for cooperating with the distributing conductor 30 and the other end exposed at the lower edge of the cap for ground contact with the distributor base 24.

From the foregoing description considered in connection with the accompanying drawing, it is believed that the construction and operation of the present ignition system will clearly be understood and its advantages appreciated. First and foremost, the uniform or non-varying intensity of the spark afforded by the present system is conducive to smooth engine operation at all speeds, second, greater power and higher engine speeds are attainable with the present system than with a system employing a so-called breaker arm, due 125 to the intensity of the spark being the same at high engine speeds as at low engine speeds; third, by reason of the spark of uniform intensity for all engine speeds, particularly efficient results are obtained from the fuel 130

consumed by the engine, especially at high speeds of the engine; and fourth, by avoiding the use of a so-called breaker mechanism, not only is the present system less expensive 5 to install and to maintain than a system employing such a mechanism, but practically all of the many disadvantages and troubles which may be traced either directly or indirectly to the breaker mechanism of systems 10 employing such a mechanism are eliminated.

While a specific structural embodiment of the invention has been illustrated and described, it will be appreciated that the invention is capable of various other specific 15 embodiments within the spirit and scope as defined in the appended claims.

I claim:

1. In a high tension ignition system, a distributor mechanism comprising a housing of 20 insulating material, spaced contacts carried thereby, a movable distributor member carrying a conductor for successive cooperation with said contacts, a source of high tension current, means whereby said high tension current is supplied to said distributor member 25 during its cooperation with said contacts and also during its entire movement between adjacent pairs of said contacts, and means between each adjacent pair of contacts for 30 grounding said conductor during a portion of the movement thereof between each adjacent pair of said contacts.

2. In an ignition system, a distributor mechanism comprising spaced contacts insulated from one another and adapted for connection with spark plugs, respectively, a distributor member movable for successive cooperation with said contacts, a source of high tension current, means whereby said 35 high tension current is supplied to said distributor member during its cooperation with said contacts and also during its entire movement between adjacent pairs of said contacts, and means to prevent the current from jumping between said distributor member and more than one of said contacts in any given 40 position of the distributor member.

3. In an ignition system, a distributor mechanism comprising spaced contacts insulated from one another and adapted for connection with spark plugs, respectively, a distributor member movable for successive cooperation with said contacts, a source of high tension current, means whereby said 45 high tension current is supplied to said distributor member during its cooperation with said contacts and also during its entire movement between adjacent pairs of said contacts, and means to prevent the current from jumping between said distributor member and more than one of said contacts in any given 50 position of the distributor member, said last mentioned means comprising a grounded contact between each adjacent pair of said first 55 mentioned contacts.

4. In a high tension ignition system, a distributor mechanism comprising a housing of insulating material, spaced contacts carried thereby, a movable distributor member carrying a conductor for successive cooperation 60 with said contacts, a source of high tension current, means whereby said high tension current is supplied to the conductor of said distributor member during its cooperation with said contacts and also during its entire 65 movement between adjacent pairs of said contacts, and means to prevent the current from jumping between the conductor of said distributor member and more than one of said contacts in any given position of the distributor member, said last named means comprising insulation completely surrounding the conductor of said distributor member between its ends, and a grounded contact between each adjacent pair of said first mentioned contacts.

In testimony whereof I hereunto affix my signature.

FRED D. NUTTALL.
